CLAIM

The ornamental design for a travel cup, as shown and described.

DESCRIPTION

FIG. 1 is a front, right, top perspective view of a travel cup, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof; and,

FIG. 8 is a bottom plan view of the enlarged scale thereof.

The dashed broken lines in the figures are for the purposes of illustrating portions of the travel cup and form no part of the claimed design.

1 Claim, 8 Drawing Sheets
